UNITED STATES PATENT OFFICE.

JOHN NAYLOR AND ROBERT THORNTON, OF STAWEll, VICTORIA.

ROCK-DRILL.

SPECIFICATION forming part of Letters Patent No. 289,800, dated November 27, 1883.

Application filed December 21, 1881. (No model.) Patented in Victoria October 10, 1881, No. 3,101; in Tasmania October 14, 1881, No. 207; in South Australia October 17, 1881, No. 209; in New South Wales November 29, 1881; in Queensland December 5, 1881, and in New Zealand January 27, 1882, No. 590.

To all whom it may concern:

Be it known that we, JOHN NAYLOR and ROBERT THORNTON, both of Stawell, in the British colony of Victoria, engineers, have invented certain new and useful Improvements in Rock-Drills, of which the following is a specification.

Our invention relates to the contrivances which we employ for regulating the supply and exhaust of the air or steam which gives the necessary motion to rock-drills. These contrivances are simple in construction, effective in operation, easily removable, (for repair,) and produce a machine which warrants us in calling ours a "noiseless" machine. They consist of certain peculiarities in the construction and arrangement of an equilibrium reversing-valve fitted, by preference, above the center of the drill-cylinder. This valve is inclosed in a cylindrical case, and is made in the form of a hollow double-ended piston-rod, on which are two hollow pistons with holes in a groove on their periphery. At the top of the case, and near each end, are small exhaust-holes, and at the bottom are ports at either end, leading to the cylinder of the drill, and at each end two valve-supply passages leading from the cylinder.

The operation is this, that at each stroke of the drill the piston thereof opens the valve-supply passages, and the air in its cylinder is conducted to the cylinder containing the equilibrium reversing-valve, forcing it to the opposite end, and thereby opening the exhaust, and also opening the supply at the other end for the return-stroke.

In order, however, that our invention may be clearly understood, we will now refer to the drawings hereto attached, in which the same letters indicate the same parts wherever they occur.

Figure 1 represents a longitudinal sectional elevation of a rock-drill constructed according to our invention; and Fig. 2, a similar view of that part of the machine which constitutes our invention, this figure being shown full size, while the others are only shown half size. Fig. 3 is a plan of the whole machine;

Fig. 4, a transverse sectional elevation on the line *a a* in Fig. 1, and Fig. 5 half-sectional elevation on line *b b* in Fig. 3.

And we would here state that we have shown the whole of a rock-drill in order the better to explain how our invention is to be applied, and not that there is anything new or of our invention in it beyond what is shown in Fig. 2, and not that our invention is not applicable to any other construction of drill, but to show one which we have found workable.

A is the cylinder of the drill, and B the piston working therein.

C and C' are the alternate supply and exhaust passages, and D and D' (shown in dotted lines) the passages which alternately conduct the compressed air or steam from the cylinder to actuate the reversing-valve.

E is the cylinder or casing of our sliding reversing-valve, the hollow pistons of which are marked F and F' and the hollow double-ended piston-rod G.

H H' are the two sets of escape-holes in the casing.

I is the space between the hollow pistons, and is for conducting the supply to the passages C and C', alternately.

J is the supply-opening from the air-reservoir or steam-boiler.

It will be seen that in the position shown in the drawings the piston B has finished its in-stroke, and the compressed air or steam which has been giving it this stroke is exhausting through C' into hollow piston F', and from thence through hollow rod G to the atmosphere. A small portion of such exhaust, having passed through passage D' and acted against the face of piston F', has reversed the equilibrium sliding valve, forcing it to the other end of its cylinder or casing E, thereby opening the port to supply-passage C for the return-stroke of the drill, the holes H' allowing the escape of the air or steam which has entered the valve-cylinder, leaving only sufficient to form a cushion on its return-stroke.

Having thus described the nature of our in-

vention and the manner of performing same, we would have it understood that our improvements in rock-drills, for which we are desirous of securing Letters Patent, are—

5 In a rock-drilling machine operating by the pressure of steam or analogous fluid, the hollow piston-rod G, adapted to discharge freely at both ends, in combination with the hollow

pistons F F', and with the main piston B and to the respective cylinders A and E, as herein specified.

JNO. NAYLOR.
ROBT. THORNTON.
